SEPARATION OF THE INDIVIDUAL FIBERS
IN FIBROUS MATERIAL

Olaf Kristoffersen, Oslo, Norway

Application January 21, 1935, Serial No. 2,738
In Sweden and Germany February 19, 1934

3 Claims. (Cl. 19—82)

This invention relates to a machine for the fine disintegration of vegetable and other substances for the purpose of producing fibrous materials. For this purpose the raw material is 5 disintegrated between stationary and revolving members by means of projections or ribs passing between one another. In order, however, to separate the material completely into individual fibers the projections are according to the invention so constructed, as distinguished from those in known apparatus, as to rub resiliently against one another, so that material between them is partly crushed and partly pulverized, thereby yielding the desired defibration. The relatively movable projections which, as in known machines, may be provided upon the periphery of a cylinder and upon the internal surface of a casing surrounding it for example, are so shaped that the projections provided on the revolving member easily enter with their front ends, having regard to the direction of movement, between the projections on the other member, but are broadened at their rear ends, so that they slide on the co-acting surfaces of the other projections, these rear ends being moreover resiliently constructed, which may be most simply arranged by longitudinally slotting the ends in question. This resilient construction of the projections may be provided either on the movable projections or upon the stationary projections only, or else on both. The projections are preferably not provided upon the entire periphery, in order that the material supplied may be distributed in the machine.

35 The machine serves primarily for the manufacture of fibrous material from wood shaving, straw, wool waste from weaving mills and other vegetable and animal waste, a small quantity of liquid being added if desired for the purpose 40 of facilitating the treatment. These substances may be mixed with binding and filling agents, this being in some instance already done in the machine. The pulpy mass is used for making insulating bodies, building slabs and many other articles.

45 In conjunction with this defibrating apparatus worm conveyers or conveying ribs are used which pass the material through the machine.

50 The invention is illustrated by way of example in the accompanying drawings, in which

55 Figure 1 shows the machine in perspective with the upper part of the frame raised, so that the construction of the machine as a whole can be seen;

Fig. 2 shows a section through the machine on the line II—II in Figure 1;

Figure 3 shows a detail on a larger scale.

The machine according to the invention consists of a hollow cylindrical frame, composed of 5 an under part 1 and an upper part 2, pivotally secured to the latter. The connection between these two parts is established on one side by means of hinges 3 and on the other side preferably by means of bolts 4. At one end of the 10 frame is provided a feeding aperture 5, through which the fibrous material is introduced into the machine. In the frame a rotor 6 is also provided, which rests in bearings 7 and 8, and which is provided with a projecting shaft 9 connected 15 with suitable driving means, not shown. Both in the upper part and in the lower part of the frame suitably spaced ribs 10 are provided. The ribs 10 do not extend round the entire circumference of the frame, but only cover about half 20 of it. When the frame is closed, therefore, there are two axially extending passages 11 and 12, through which the material can pass in a longitudinal direction without moving between the individual ribs. The ribs 10 may advantageously 25 be secured to the frame throughout their length, and they are preferably of wedge-like shape, so that the end 13 which is the leading end having regard to the direction of movement 30 is narrower than the rear end 14. In this manner, therefore, the spaces between the individual ribs 10 are wider at the front end than at the rear end.

35 The rotor 6 is provided at one end immediately underneath the feeding aperture 5, preferably with a feeding screw 15, which, when material is introduced through the feeding aperture 5, immediately conveys it through the machine in an axial direction, thereby forcing it between the cooperating ribs. In a portion of the axial length corresponding to the portion of the frame provided with ribs 10 the rotor is provided with a number of ribs 16. The ribs 16, as will be seen more particularly from Figure 3, are formed of a compact front end 17 and a dovetail-shaped rear end 18 formed with two branches 19 and 20. The ribs 16 are secured to plate-like rings 21 (see Figure 2) by means of a dovetail-shaped wedging device 22, engaging in corresponding recesses or keyways extending in 40 an axial direction through the rings 21. In this manner only the solid portion 17 of the ribs 16 is rigidly connected with the rings 21 of the rotor. The rings 21 are also connected by the aid of suitable keys 23 with the rotor shaft 9. 45

35

40

45

50

55

The ribs 16 are preferably made of a hard resilient material, and the external dimension between the two branches 19 and 20 of the dovetail is preferably made somewhat greater than 5 the minimum distance between the ribs 10 in the frame.

The individual ribs 16, as shown in Figure 1, are spirally arranged round the rotor 6, and are at such an axial distance from one another, that 10 they fit the spaces between the ribs 10 in the frame. Furthermore the front end 17 of each of the ribs 16 is bevelled along a line which corresponds approximately to the spiral line along which the ribs are arranged round the rotor.

15 Each of the rings 21 may advantageously be provided with two ribs, one on each side, as shown in Figures 1 and 3, and between each ring 21 there may be provided an intervening ring 24, which is not provided with ribs, and which serves 20 to keep the ribs a suitable distance apart.

The material conveyed through the machine leaves the machine at the right hand and through the aperture 25 in the bearing 7, after 25 which it escapes through the aperture 26. The treatment of the material has here been finally completed, the individual fibers having been separated from one another without injury.

To enable the machine to be kept at any time at a desired temperature, the shaft 9 is made 30 hollow, so that means for cooling by the aid of a suitable liquid can be provided without difficulty. The under part 1 as well as the upper part 2 of the frame may also be provided with cooling ducts 27 and 28 respectively.

35 I claim:—

1. Improvements in means for separating the individual fibers of fibrous substances, comprising a stationary drum and a cylinder revolving therein, projecting rib-like teeth on both members in planes at right angle to the cylinder axis, said teeth being arranged in such 40

a way that they will mesh with each other, and one of these sets of ribs being arranged in such a way that they will exert a resilient pressure against the sides of the projecting ribs on the other set, when they are in mesh with each other, the said resilient ribs being fastened only at their front end and by means of undercut keys and keyways, while the rear portion is longitudinally slotted and is free to bear resiliently against the other set of ribs. 5

2. Improvements in means for separating the individual fibers in fibrous substances as in claim 1, characterized by the feature that the resilient ribs bear with their front portion (having regard to the direction of running) upon the 15 cylinder, and are connected with the latter by undercut keys and keyways, while the rear portion, which is longitudinally slotted, is free, and bears resiliently against the ribs on the stationary drum. 10

3. Improvements in means for separating the individual fibers of fibrous substances, comprising a stationary drum and a cylinder revolving therein, projecting rib-like teeth on both members in planes at right angle to the cylinder axis, 25 said teeth being arranged in such a way that they will mesh with each other, and one set of these ribs being arranged in such a way that they will exert a resilient pressure against the sides of the projecting ribs on the other set when 30 they are in mesh with each other, the said resilient ribs being fastened only at their front end and by means of undercut keys and keyways, while the rear portion is longitudinally slotted and is free to bear resiliently against the other 35 set of ribs, the dimensions in the axial direction of the cylinder of the longitudinally slotted end of the said resilient ribs being greater than the distance between the teeth in the other set of ribs. 40

OLAF KRISTOFFERSEN.
